UNITED STATES PATENT OFFICE.

SAHATIEL G. MANDALIAN, OF NORTH ATTLEBORO, MASSACHUSETTS.

DESIGN FOR AN ORNAMENTAL PLATE FOR A BAG FRAME.

Application filed July 21, 1924. Serial No. 10,204. Term of patent 7 years.

To all whom it may concern:

Be it known that I, SAHATIEL G. MANDALIAN, a citizen of the United States, residing at North Attleboro, in the county of Bristol and State of Massachusetts, have invented a certain new, original, and ornamental Design for an Ornamental Plate for a Bag Frame, of which the following is a specification.

In the accompanying drawings which form a part of this specification,

I claim:

The ornamental design for an ornamental plate for a bag frame, as shown.

SAHATIEL G. MANDALIAN
